DENTAL FLOSS APPLICATOR AND DISPENSER

Fred M. Gore, 1919 Walnut Plaza, Apt. 2024,
Carrollton, Tex. 75006

Filed Aug. 20, 1973, Ser. No. 389,580

Term of patent 3½ years

Int. Cl. D24—99

U.S. Cl. D24—1 D

FIG. 1.

FIG. 2.

FIG. 3.

FIG. 4.

FIG. 5.

FIG. 6.

FIG. 1 is a top plan view of a dental floss applicator and dispenser showing my new design;

FIG. 2 is a front side elevation view thereof;

FIG. 3 is a dispensor end elevation view thereof;

FIG. 4 is a bottom plan view thereof;

FIG. 5 is a rear side elevation view thereof; and

FIG. 6 is an applicator end elevation view thereof.

I claim:

The ornamental design for a dental floss applicator and dispenser, substantially as shown.
